UNITED STATES PATENT OFFICE

96,608

DESIGN FOR A SHOE

Kenneth B. Keyes, New York, N. Y., assignor to Bancroft Walker Co., Waltham, Mass., a corporation of Massachusetts

Application July 2, 1935, Serial No. 57,491

Term of patent 3½ years

To all whom it may concern:

Be it known that I, Kenneth B. Keyes, a citizen of the United States, residing in New York, in the county of New York and the State of New York, have invented a new, original, and ornamental Design for a Shoe, of which the following is a specification, reference being had to the accompanying drawing, forming a part thereof, in which

Fig. 1 is a view in side elevation of a shoe showing my new design;

Fig. 2 is a plan view of the shoe positioned with its longitudinal axis horizontal.

I claim:

The ornamental design for a shoe substantially as shown and described.

In testimony whereof, I have affixed my signature hereto.

KENNETH B. KEYES.
